UNITED STATES PATENT OFFICE.

HELGO WIGGO JESPERSEN, OF WESTERN SPRINGS, ILLINOIS, ASSIGNOR TO WESTERN ELECTRIC COMPANY, INCORPORATED, OF NEW YORK, N. Y., A CORPORATION OF NEW YORK.

MECHANISM FOR WORKING PULPOUS MATERIAL.

Application filed May 16, 1924, Serial No. 713,703. Renewed November 18, 1926.

This invention relates to improvements in mechanism for working pulpoous material, and more particularly to mechanism for forming such material to constitute a homogeneous coating for cores in strand form such as wire, and the like.

Mechanisms made in accordance with this invention are particularly well adapted for use in connection with the method and apparatus for coating cores disclosed in the co-pending application of H. G. Walker, Serial No. 621,242, filed February 26, 1923, but it is to be understood that the invention is not limited to such use, but only in so far as defined by the appended claims.

An object of the invention is to provide a forming mechanism which can be adjusted while in operation.

Another object of the invention is to provide a forming mechanism wherein a forming member yieldingly engaging the pulpoous material on a core can be adjusted during the operation of the forming mechanism.

A further object of the invention is to provide a forming mechanism which can be adjusted while in operation and which will not strip the coating from the core while in operation.

A forming mechanism embodying the invention comprises a plurality of plates disposed in opposed relation and pivotally mounted in a rotatable carrier in positions wherein they are adapted to engage the pulpoous material on a core being drawn through the forming mechanism. Springs connect the plates to an annular member slidably journaled on the carrier and adapted to be longitudinally displaced in either direction while the forming mechanism is in operation. Means is provided to rotate the annular member with respect to the rotatable carrier during such longitudinal displacement of the annular member and this rotation is utilized to increase or decrease the pressure with which the plates engage the pulpoous material on the core, the torsion of the springs being increased when the rotation is in one direction and being decreased when the rotation is in the other direction.

Further objects of the invention will become apparent as the detail description progresses, reference being had to the accompanying drawing, wherein

Fig. 1 is an elevation of a forming mechanism embodying the invention;

Fig. 2 is a section taken on line 2—2 of Fig. 1;

Fig. 3 is a section taken on line 3—3 of Fig. 2;

Figs. 4 and 5 are enlarged sectional views illustrating the manner in which the pulp is applied to the core before it is delivered to the forming mechanism shown in Fig. 1, and

Figs. 6 and 7 are enlarged sectional views showing the forming of the pulp coating during the forming operation and after the completion of the forming operation respectively.

The forming mechanism shown in the accompanying drawing is especially adapted to be used in conjunction with apparatus shown in the aforementioned application of H. G. Walker, which apparatus is adapted to apply pulpoous material to a core and comprises a foraminous member and a plurality of felt covered squeezing rolls. In the operation of this apparatus the core is first brought into contact with pulpoous material deposited upon the foraminous member, and then an additional amount of pulpoous material is deposited upon the core and the foraminous member. The pulp so deposited and the core are then brought into contact with one of the squeezing rolls which cooperates with the foraminous member to squeeze out the "free liquid" so to speak in the pulp coating. The partially dried pulp adheres to the felt of the squeezing roll in the form of a ribbon with the core substantially centrally located therein as shown in Fig. 4 of the accompanying drawing, and the core with the pulp ribbon attached thereto passes around the roll and between it and its cooperating roll, the contour imparted to the ribbon by the squeezing rolls being shown in Fig. 5.

The forming mechanism embodying the features of the present invention is designed to receive the core and its ribbon from the squeezing rolls and to wrap the projecting edges of the ribbon around the core and around each other until it conforms substantially to the shape of the core. The appearance of the coating after it is first acted upon by the forming mechanism is shown in Fig. 6, and the appearance thereof after the

forming action is completed is shown in Fig. 7.

Referring to the drawings, the forming mechanism comprises a rotatable carrier 10, the rotatable carrier in turn comprising a tubular member 11 rigidly secured to and between a plurality of cup-shaped collars 12 and 13. Integral with each of the collars 12 and 13 is a sleeve, the sleeves being designated by the reference characters 14 and 15 respectively, and being rotatably mounted in suitable bearings 16, 17 and 18. A friction wheel 19 splined upon the sleeve 15 engages a friction disc 20 rigidly secured 10 to a shaft 21 which is rotatably journaled by any suitable means (not shown). The friction wheel 19 and the friction disc 20 provide means whereby the carrier 10 may be rotated, the friction disc 20 being driven 15 by suitable means (not shown). The speed of the rotatable carrier 10 may be varied by adjusting the friction wheel 19 with respect to the axis of rotation of the friction disc 20, the friction wheel 19 being positioned 20 between the bifurcations of a bifurcated bracket 22 slidably journaled upon a rod 23 projecting from the bearing 18. A set screw 24 threaded into the bracket 22 is employed to rigidly secure the bracket 22 and the 25 friction wheel 19 in an adjusted position with respect to the friction disc 20. Disposed within the tubular member 11 are a plurality of forming members, each of 30 which comprises a plate 25, the plates 25 being disposed in opposed relation. Each plate 25 is pivotally mounted between the collars 12 and 13, a plurality of trunnions 35 being provided for this purpose. One end of each plate 25 is adapted to engage the pulpos material on a core being drawn 40 through the forming mechanism, and the other end of the plate is rigidly secured to one end of one of a plurality of springs 27 by means of rivets 28, the other end of each 45 spring 27 being rigidly secured to an annular member 29 slidably journaled upon the tubular member 11. It will be noted that the tubular member 11 is provided with a plurality of slots 30 adapted to accommodate 50 the springs 27, and that the annular member 29 is provided with a slot 31 which is angularly disposed with respect to the axis of the annular member. The slot 31 cooperates with a pin 32 projecting from the 55 tubular member 11 to angularly displace the annular member 29 with respect to the tubular member 11 when the annular member is moved along the tubular member in either direction. The arrangement is such that if 60 the annular member 29 is moved to the left (Fig. 2) it will be displaced in a counter-clockwise direction (Fig. 3) with respect to the tubular member, and the springs 27 will tend to rotate the plates 25 around their 65 pivotal axes to bring them closer to the axis

of rotation of the tubular member 11. In a like manner, if the annular member 29 is moved to the right (Fig. 2) it will be angularly displaced in a counter-clockwise direction (Fig. 3) with respect to the tubular member 11, and the springs 27 tend to rotate the pulp engaging ends of the plates 25 in directions which will cause them to draw away from the axis of rotation of the tubular member 11. 75

The annular member 29 may be moved in either direction during operation of the forming mechanism and it is provided with an annular flange 34 which may be engaged by any suitable tool and forced in the desired direction. 80

In the operation of a forming mechanism, the core carrying a ribbon of pulpos material as illustrated in Fig. 5 is drawn through the sleeve 14 and into engagement 85 with the plates 25, which first operate on the ribbon of pulpos material to shape it as shown in Fig. 6. The plates 25 continue to wrap the ribbon around itself and around the core until it is drawn through the sleeve 90 15, the contour of the pulpos material when it leaves the plates 25 being shown in Fig. 7. If during the operation of the forming mechanism the operator wishes to increase 95 or decrease the pressure of the plates upon the pulpos material, it is only necessary to move the annular member 29 in the proper direction. It is apparent that the forming mechanism may be adjusted in this manner to properly form the pulpos material 100 around the cores of various diameters. 105

What is claimed is:

1. In a mechanism for working pulpos material on a core, a forming member yieldingly engaging the pulpos material, means for causing relative movement between the forming member and the pulpos material, and means operable during said movement for adjusting the forming member. 110

2. In a mechanism for working pulpos material on a core, yielding means engaging the pulpos material, means for causing relative movement between the yielding means and the pulpos material, and means for adjusting the yielding means during 115 said relative movement.

3. In a mechanism for working pulpos material on a core, a plurality of forming members yieldingly engaging the pulpos material, means for causing relative movement between the forming members and the pulpos material, and means operable during 120 said relative movement for simultaneously adjusting the forming members.

4. In a mechanism for working pulpos material on a core, a plurality of opposed forming members yieldingly engaging the pulpos material, means for causing relative movement between the forming members and the pulpos material, and means oper- 125

- able during said movement for adjusting the forming members.
5. In a mechanism for working pulpous material on a core, a plurality of opposed forming members yieldingly engaging the pulpous material, means for causing relative movement between the forming members and the pulpous material, and means operable during said movement for simultaneously adjusting the forming members. 10
6. In a mechanism for working pulpous material on a core, a rotatable forming member yieldingly engaging the pulpous material, and means operable during the rotation of the forming member for adjusting the forming member. 15
7. In a mechanism for working pulpous material on a core, a forming member yieldingly engaging the pulpous material, means for causing relative rotary movement between the pulpous material and the forming member, and means operable during the relative rotary movement for adjusting the forming member. 20
8. In a mechanism for working pulpous material on a traveling core, a forming member yieldingly engaging the pulpous material, means for causing relative lateral movement between the pulpous material 25 and the forming member, and means operable during the relative lateral movement for adjusting the forming member.
9. In a mechanism for working pulpous material on a traveling core, a forming member yieldingly engaging the pulpous material, means for rotating the forming member around the core, and means operable during the rotation of the forming member for adjusting the forming member. 30
10. In a mechanism for working pulpous material on a core, a rotatable pressure member yieldingly engaging the pulpous material, and means operable during the rotation of the pressure member for adjusting the pressure member. 40
11. In a mechanism for working pulpous material on a core, a plurality of rotatable members yieldingly engaging the pulpous material, and common means for adjusting the said members during rotation thereof. 50
12. In a mechanism for working pulpous material on a core, a plurality of spring pressed rotatable members engaging the pulpous material, and means for adjusting the spring pressed members during rotation thereof. 55
13. In a mechanism for working pulpous material on a core, a plurality of rotatable members yieldingly engaging the pulpous material and disposed in opposed relation, and means for adjusting said members during rotation thereof. 60
14. In a mechanism for working pulpous material on a core, a plurality of pressure members yieldingly engaging the pulpous
- material, means for rotating said members around the core, and means for adjusting said members during rotation thereof.
15. In a mechanism for working pulpous material on a core, a plurality of forming members yieldingly engaging the pulpous material, means for rotating said members around the core, and common means for adjusting said members during rotation thereof. 70
16. In a mechanism for working pulpous material on a core, a forming member yieldingly engaging the pulpous material, means for causing a relative movement between the forming member and the pulpous material, and means including an element encircling the core for adjusting the forming member during said relative movement. 75
17. In a mechanism for working pulpous material on a core, a forming member yieldingly engaging the pulpous material, means for causing a relative movement between the forming member and the pulpous material, and means including a rotatable element 80 for adjusting the forming member during said relative movement.
18. In a mechanism for working pulpous material on a core, a forming member yieldingly engaging the pulpous material, means for causing a relative movement between the forming member and the pulpous material, and means including a rotatable element encircling the core for adjusting the forming member during said relative movement. 85
19. In a mechanism for working pulpous material on a core, a forming member yieldingly engaging the pulpous material, and means operable during the operation of the forming mechanism for regulating the force with which the forming member engages the pulpous material. 90
20. In a mechanism for working pulpous material on a core, a plurality of forming members yieldingly engaging the pulpous material, and means operable during the operation of the forming mechanism for simultaneously regulating the force with which the forming members engage the pulpous material. 110
21. In a mechanism for working pulpous material on a core, a rotatable carrier, a forming member mounted upon the carrier, and means operable during the rotation of the carrier for adjusting the forming member. 115
22. In a mechanism for working pulpous material on a core, a rotatable carrier, a forming member mounted upon the carrier, and means mounted on the carrier and operable during rotation thereof for adjusting the forming member. 120
23. In a mechanism for working pulpous material on a core, a rotatable carrier, a forming member mounted upon the carrier, and means slidably journaled on the carrier 125
- 130

for adjusting the forming member during rotation of the carrier.

24. In a mechanism for working pulpos material on a core, a rotatable carrier, an annular member disposed around the carrier and movable longitudinally thereof, means for rotating the annular member relative to the carrier, during said longitudinal movement, and a forming member carried by the annular member and yieldingly engaging said pulpos material.

25. In a mechanism for working pulpos material on a core, a rotatable carrier, means mounted upon the carrier and movable longitudinally thereof, means for rotating the said first mentioned means relative to the carrier during said longitudinal movement, and a forming member carried by said first mentioned means.

In witness whereof, I hereunto subscribe my name this 1st day of May, A. D. 1924.

HELGO WIGGO JESPERSEN.
